MOTORCYCLE FOOTPEG

John L. Corey, 21329 S. Martin St.,
Carson, Calif. 90744

Filed Jan. 2, 1973, Ser. No. 320,078

Term of patent 14 years

Int. Cl. D12—11

U.S. Cl. D12—114

FIG. 1

FIG. 2

FIG. 1 is a front isometric view of a motorcycle footpeg showing my new design; and

FIG. 2 is a rear isometric view thereof; showing a second embodiment of my design, the sole difference being in the spiral, which is opposite that of FIG. 1.

I claim:

The ornamental design for a motorcycle footpeg, as shown.
